(57) **CLAIM**

The ornamental design for a swivel disk light, as shown and described.

DESCRIPTION

FIG. 1 is a front, top perspective view of a swivel disk light showing my design therefor;

FIG. 2 is a bottom perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is a front, top perspective view of a second embodiment showing the disk in a rotated orientation;

FIG. 10 is a bottom perspective view of the second embodiment showing the disk in an alternative rotated orientation;

FIG. 11 is a front elevational view of the second embodiment showing the disk in a rotated orientation;

FIG. 12 is a rear elevational view of the second embodiment showing the disk in a rotated orientation;

FIG. 13 is a right side view of the second embodiment showing the disk in a rotated orientation;

FIG. 14 is a left side view of the second embodiment showing the disk in a rotated orientation;

FIG. 15 is a top plan view of the second embodiment showing the disk in a rotated orientation; and,

FIG. 16 is a bottom plan view of the second embodiment showing the disk in an alternative rotated orientation.

The broken lines shown in the drawings depict portions of the swivel disk light that form no part of the claimed design.

1 Claim, 16 Drawing Sheets
